UNITED STATES PATENT OFFICE.

LOUIE ENDER, OF WATERTOWN, SOUTH DAKOTA.

WEATHER-STRIP.

1,229,920.

Specification of Letters Patent. Patented June 12, 1917.

Application filed January 27, 1916. Serial No. 74,641.

To all whom it may concern:

Be it known that I, LOUIE ENDER, a citizen of the United States, residing at Watertown, in the county of Codington and State 5 of South Dakota, have invented a new and useful Weather-Strip, of which the following is a specification.

This invention relates to improvements in weather strips, and more particularly to that 10 type which is adapted to be secured adjacent the lower end of a door, storm shutter or the like, to effectively close the space or usually existing between the door and the door-sill or threshold.

15 An object of this invention is to provide a weather strip which is adapted to resiliently engage the door sill or threshold and to be automatic in its operation.

Another object of the present invention is 20 to provide a weather strip having its coöperating members housed against the admission of rain, snow or other extraneous matter, and which can be applied to doors of various widths.

25 A further object of the invention is to provide a weather strip of generally improved construction, whereby the device will be simple, durable and inexpensive in construction, as well as convenient, practi- 30 cal, serviceable and efficient in its use.

With the foregoing and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed without departing 40 from the spirit of the invention.

The invention has been illustrated in its preferred embodiment in the accompanying drawings, wherein:—

Figure 1 is a perspective view of the im- 45 proved weather strip, depicting it applied to a door.

Fig. 2 is a vertical transverse sectional view, showing the hinged strip in its lowered position.

50 Fig. 3 is a similar view, but illustrating the hinged strip in elevated position.

Fig. 4 is a fragmental detail perspective view of the improved stationary guard strip, showing its component members separated.

55 Fig. 5 is a detail perspective view of one end of the improved hinged strip.

In carrying out the present invention, there is provided a stationary guard strip comprising two sections, A and B respectively. The sections A and B are provided 60 with downwardly and outwardly extending portions 1, which are provided at their lower ends with inwardly extending resilient lips 2, while at their outer ends they are provided with inwardly extending triangular walls 3. 65

Attaching flanges 4 are formed about the upper edges of the members 1 and the inner edges of the walls 3. The flanges 4 are provided with apertures for the reception of screws or other securing elements 5, which 70 secure the complete stationary guard to the door D.

In order to prevent driving rain or snow from entering the upper edge of the stationary guard strip, inwardly projecting 75 flanges 6 extend from the upper edge of attaching flanges 4 into a groove 7 formed in the door D.

The inner end of the section B is reduced to provide an ear 8, which is overlapped by 80 the inner end of the section A, thereby forming a continuous strip.

A hinged strip 9 is provided which is adapted to coöperate with the stationary guard strip. This strip comprises a relatively thick plate 10, which may be formed of band-steel or other suitable metal, and a relatively thin covering 11, which is bent adjacent its inner edge to form a groove 12 for the reception of the inner edge of the 90 body plate 10. The covering 11 extends from the groove 12 along the bottom of the plate 10, thus forming a bottom covering member 13, which is bent around the outer edge of the plate 10 to form a top covering 95 member 14, that extends inwardly beyond the inner edge of the plate 10, where it is bent outwardly to form a securing lip 15, which in turn coöperates with the resilient lip 2, as will be hereinafter disclosed. 100

Suitable hangers or supporting members 16 are provided, which are secured to the hinged strip 9 by rivets 17. The rivets 17 pass through the body plate 10 and the bottom covering members 13 of the hinged strip 9, but they do not extend through the top covering member 14, thus it is obvious that the top covering member 14 conceals the rivet 17, thereby presenting a smooth uninterrupted surface. 105

Apertures 18 are provided at the inner terminals of the hinge members 16 for the 110

reception of the intermediate portions of staples or other securing elements 19, which are driven into the door D.

A guide member is secured to the door-sill 5 or threshold and comprises a relatively thick strip 20, which conforms to the contour of the door-sill or threshold, and a relatively thin strip 21, that is shaped similar to the thick strip 20 and is secured thereupon.

10 Secured to the door casing C and in the path of travel of the door D, is a stop member 22, which has its inner edge 23, or that edge which is disposed adjacent the door D, shaped to conform to the contour of the 15 outer faces of the stationary guard strip A—B and the hinged strip 9.

In practical use (assuming that the door is open as shown in Fig. 1), the door D in closing will cause the lower edge of the 20 hinged member to engage the outer face of the strip 21, which in turn will guide the lower edge of the hinged member up and across the door-sill or threshold, until the movement of the door is checked by the stop 25 member 22.

It will be observed that the resilient lip 2 engages the upper face of the top covering 30 member 14 adjacent the securing lip 15, and presses down upon the covering member 14, thereby forcing the entire hinged strip 9 downwardly about its pivot 19, until the securing lip 15 engages the resilient lip 2 and thereby limits its downward movement of the hinged member 2, as shown in Fig. 2.

35 The hinged strip 9 may be shortened to fit a relatively narrow door by simply cutting off the desired length, and the stationary guard strip A—B may be readily shortened by cutting from the inner end of the section 40 A, the desired length, thus it is obvious that this device may be applied to doors of various widths.

It is manifest from the foregoing, that 45 this device will effectively prevent rain or snow from entering between the lower edge of the door and the door-sill, and since the cooperating members are all housed, the device will be thoroughly protected against all extraneous matter which would tend to impede its operation.

Attention is directed to the fact that the covering plate 11 is doubled on a longitudinal line to provide upper and lower portions 14 and 13 overlying and underlying the rela-

tively thick plate 10 which is elongated and 55 inclined transversely, with the bend of the covering plate adjacent to the lower edge of the plate 10, the edge of the lower portion 13 being bent back upwardly, as at 12, over the upper edge of the plate 10 to secure them 60 together, and the upper portion 14 extending over the bent back edge and being hinged to the supporting member. The members or tongues 16 which overlap the lower portion 13 of the plate 11 project beyond the bent back edge 12, and the rivets 17 which engage through said tongues, lower portion 13 and plate 10, are covered and protected by the upper portion 14. This prevents moisture from flowing around the 70 rivets 17, thereby avoiding rust and corrosion, it being noted that the strip 9 is subjected to adverse conditions by its exposure to the elements. Furthermore, the upper portion 14 of the plate 11 being detached 75 enables said upper portion and plate 10 to be sprung apart, which may be useful on certain door structures.

Having thus described the invention, what is claimed as new is:

80 A weather strip embodying an elongated transversely-inclined relatively-thick plate, a covering plate doubled on a longitudinal line to provide upper and lower portions overlying and underlying the first mentioned plate with the bend of the covering plate adjacent to the lower edge of the first mentioned plate, the edge of the lower portion of the covering plate being bent back upwardly over the upper edge of the first mentioned plate, said upper portion of the covering plate extending over said bent back edge and being adapted to be hinged to a supporting member, tongues overlapping 85 said lower portion of the covering plate and projecting beyond said bent back edge, and rivets engaging through said tongues, lower portion of the covering plate and first mentioned plate and covered by said upper portion of the covering plate.

90 In testimony that I claim the foregoing as my own, I have hereto affixed my signature in the presence of two witnesses.

100

LOUIE ENDER.
